UNITED STATES PATENT OFFICE.

LEWIS KIDD, OF BLOOMFIELD, INDIANA.

SMOKE-CONSUMER.

1,090,072.

Specification of Letters Patent. Patented Mar. 10, 1914.

Application filed January 31, 1913. Serial No. 745,511.

To all whom it may concern:

Be it known that I, LEWIS KIDD, citizen of the United States, residing at Bloomfield, in the county of Greene and State of Indiana, have invented certain new and useful Improvements in Smoke-Consumers, of which the following is a specification.

My invention relates to new and useful improvements in waste conveying systems and the object of my invention is to provide a system which may be used in factories, mills and the like for conveying smoke from the stacks and disposing of the same.

A further object of my invention is to provide a system in which the smoke is conveyed through the action of air forced through conveyer pipes or tubes the continual draft of air also furnishing a forced draft for the furnace or the like.

20 A further object of my invention is to so arrange the system that the smoke may be conveyed any desired distance by the employment of auxiliary blowers positioned at spaced intervals along the conveyer pipe. 25 And a still further object of my invention is to lead the smoke into a sewer pipe and to provide means for forcing the smoke through the sewer pipe.

With these and other objects in view, my 30 invention will be more fully described, illustrated in the accompanying drawings, and then specifically pointed out in the claims which are attached to and form a part of this application.

35 The drawing is an elevational view, partially in section, showing my improved waste handling system employed as a smoke consumer.

Corresponding and like parts are referred 40 to in the following description and indicated in all the views of the drawings by the same reference characters.

My invention is intended primarily as a smoke consumer and the system when so employed is preferably connected between the stack 10 of the furnace 11 and a sewer pipe 12 through which the smoke is to be passed. When so employed, a pipe 13 made up of any suitable number of sections according 45 to the length and direction in which it must pass, is connected by one end to the stack 10 of the furnace, extends through the wall of the building and is connected by its other end to a T-branch 14 of the sewer pipe 12. 50 This pipe 13 is provided intermediate its length with a plurality of blower fans 15

and 16 which may be of any suitable type of construction and which are driven by motors 17, the motors being supported upon suitable brackets 18 or within housings 19, 60 as preferred. The fans may be driven by these motors either by means of a belt 20, trained over pulleys 21 and 22 of the motor and fan shafts respectively, or by means of the same belt, trained over the pulley of the 65 motor and a pulley 23 of a shaft 24 which passes into the pipe 13 and carries a bevel gear 25 meshing with a bevel gear 26 carried by the fan shaft. As many of these blowers may be provided as found desirable 70 to create a sufficient draft through the pipe 13 and it will of course be apparent that this draft, because of its suction, forms in effect a forced draft for the furnace itself.

The smoke upon entering the sewer pipe 75 12 immediately becomes cooled and any solid particles of soot or other foreign matter settle in the pipes and are washed through the same while the gases themselves also pass through the pipe. In order to insure the ready passing of the gases through the sewer pipe, the latter is preferably provided at spaced intervals with inspirator tubes 27 extending from motor operated blowers 28, the free ends of the tubes 27 80 being directed toward the lower end of the pipe 12. The blowers 28 are preferably mounted in housings 29 positioned in the ground above the pipe 12 and extending by their upper ends above the ground level, being 85 there provided with ventilator caps 30 spaced above the upper ends of the housings to permit an inrush of air to the blowers.

The above described system forms an exceptionally effective smoke consumer in that 90 it also forms a forced draft for the furnace.

It will of course be understood that I do not wish in any way to limit myself to the specific details of construction illustrated in the drawings and above described as minor 100 changes may at any time be made, if desired, without in the slightest degree departing from the spirit of my invention.

It will further be understood that a single conveying and discharge pipe may be connected by a number of draft pipes to a number of furnace stacks and that when so arranged the system will operate as effectively as when connected to but a single furnace.

Having thus described the invention, what 110 is claimed as new is:

1. In a smoke disposal system, the combi-

nation with a sewer pipe, of a plurality of housings located in the ground at spaced intervals along said pipe, ventilating caps covering said housings, a blower positioned in 5 each of said housings, an inspirator tube leading from each blower into the sewer pipe with its free end directed toward the discharge end of said pipe, and means for conducting smoke from a stack to the sewer 10 pipe, said means including a smoke conveying pipe leading from the stack to the sewer pipe, and blowers interposed in said smoke conveying pipe.

2. In a smoke disposal system, the combi-

nation with a sewer pipe, of a plurality of 15 housings located in the ground at spaced intervals along said pipe, a blower positioned in each of the housings and arranged to force air through the sewer pipe, and means for conducting smoke from the stack to the 20 sewer pipe.

In testimony whereof I affix my signature in presence of two witnesses.

LEWIS KIDD. [L. S.]
